UNITED STATES PATENT OFFICE.

ALBERT HAUCK, OF JEWETT, OHIO.

DOOR-STOP.

SPECIFICATION forming part of Letters Patent No. 475,686, dated May 24, 1892.

Application filed October 15, 1891. Serial No. 408,789. (No model.)

To all whom it may concern:

Be it known that I, ALBERT HAUCK, a citizen of the United States, residing at Jewett, in the county of Harrison and State of Ohio, 5 have invented certain new and useful Improvements in a Combined Door Stop and Check; and I do hereby declare the following to be a full, clear, and exact description of the invention, such as will enable others skilled 10 in the art to which it appertains to make and use the same.

This invention relates to a combined door check, stop, and lock.

The object of the invention is to provide in 15 a single simple structure a combination of elements for efficiently and conveniently effecting the desired results.

The improvement consists of the novel features and the peculiar construction and combination of the parts, which will be hereinafter more fully described and claimed, and 20 which are shown in the annexed drawings, in which—

Figure 1 is a perspective view of the invention, showing its application. Fig. 2 is a vertical central section of the device. Fig. 3 is a detail side view of the upper end of the case, showing the inclined end for holding the door-check in position and the door-stop clear of 25 the floor.

The sheath or casing A is open at each end and is provided with lateral wings a, which are apertured to receive the fastening-screws by means of which the device is secured to 30 the door. The bore of the sheath is reduced at its upper end to receive the shank b of the stop B. The slot d in the side of the casing receives the check C, which is carried by and secured to the shank of the stop and guides 35 the latter in its vertical movements. The check is sufficiently long to prevent the knob or key from injurious contact with the plastering and serves as a handle to manipulate 40 the stop. The outer end of the check is provided with the rubber bumper c. The lower

end of the stop is provided with a shoe b', of rubber or other yielding material, to obtain a purchase on the floor and hold the door in the required position. The spring H is located in the enlarged portion of the sheath and is confined between the shoulder f at the base of the shank b and the shoulder e at the inner end of the reduced portion of the casing. 50

The device is secured to the inner lower corner of the door, and when required to be 55 used as a stop to hold the door open at the desired angle the check C is brought in register with the slot d, when the spring H will force the stop in engagement with the floor. To use the device as a check, the portion C is 60 turned at right angles to the door and is supported on the inclined end of the casing. As a lock, an opening is bored in the floor to receive the lower end of the stop.

Having thus described my invention, what 65 I claim, and desire to secure by Letters Patent, is—

The hereinbefore shown and described combined door stop and check, consisting of case A, having ears a, which are apertured to receive the fastening devices, the bore of the case being reduced at its upper end to form the shoulder e and slotted at d and having the upper end of the case inclined downwardly from the sides of the slot d, the stop 70 B, having shoulder f and adapted to press upon the floor, the spring mounted on the stop and adapted to be held between the shoulders e and f, and the handle C, provided to manipulate the stop B and adapted to strike against 75 the wall and prevent injurious contact of the key or knob with the said wall, substantially as set forth.

In testimony whereof I affix my signature in presence of two witnesses.

ALBERT HAUCK.
